HIS ATTORNEYS.

UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed December 13, 1926. Serial No. 154,432.

This invention relates principally to flexible car roofs wherein metal roof sheets are loosely connected along their adjacent margins by weatherproofing seams that permit 5 relative movement of said sheets to a limited extent so that they are enabled to accommodate themselves to the distortions of the car frame.

The principal object of the present invention is an improved seam construction which will secure an independent sluing or oscillatory movement of the roof sheets about points located near their adjacent margins. Other objects are simplicity, durability and 15 cheapness of construction.

The invention consists principally in the seam construction hereinafter described; and it also consists in the parts and in the combinations and arrangements of parts herein- 20 after described and claimed.

In the accompanying drawing, which forms part of this specification and wherein like symbols refer to like parts wherever they occur,

25 Fig. 1 is a plan view of a ridge portion of a flexible outside metal roof provided with a ridge seam construction embodying my invention;

Fig. 2 is a vertical cross section through 30 the ridge seam on the line 2—2 in Fig. 1;

Fig. 3 is a perspective view of one of the pivot pieces;

Fig. 4 is a plan view of a modified ridge 35 seam construction; and

Fig. 5 is a vertical section on the line 5—5 in Fig. 4.

Referring to the drawings, the invention is 40 illustrated in connection with a flexible outside metal car roof comprising metal roof sheets 6 resting on the wooden sheathing 7, which is supported at the ridge on a wooden ridge pole 8. The metal roof sheets 6 are arranged in two rows, one on each side of the ridge, the sheets on opposite sides of the 45 ridge being spaced apart; and the sheets on the same side of the ridge are loosely positioned between wooden mullions or battens 9 arranged transversely of the car and secured on the roof sheathing 7.

50 The side and ridge margins of the roof sheets are bent up and are thence rebent inwardly and downwardly over the body portions of the sheets to form upstanding side and ridge marginal seam flanges or ribs 10

and 11, respectively. Side seam covers or 55 caps 12 of substantially inverted channel-shaped section straddle the adjacent side seam flanges or ribs 10 of the roof sheets and the battens located therebetween. The adjacent ridge seam flanges 11 of said sheets 60 are connected by means of inverted channel-shaped ridge covers 13 that straddle said ridge seam flanges and have outstanding base flanges 14 that rest on the body portions of 65 said sheets inside the ridge and side seam flanges thereof. The adjacent ends of the ridge seam covers 13 and the side seam covers 12 are connected together and secured to the car by means of the usual four-way 70 center corner caps 15 that are secured to the car by vertical bolts 16, which also secure the running board saddles (not shown) in position.

The body portion of each roof sheet is 75 pressed up near the ridge end of said sheet substantially midway of its side margins to form an upstanding convexo-concave or crescent shaped boss or rib 18, which is located inside the ridge seam cover and is arranged with its convex side facing the inside surface of the side flange thereof. Located between the spaced ridge flanges of adjacent 80 sheets substantially midway of the length of their ridge flanges and in line with the convexo-concave or crescent bosses 18 thereof 85 is a convexo-convex or lens shaped ridge piece 19. Said ridge piece preferably comprises a sheet metal member of substantially inverted channel-shaped section with outstanding base flanges 20 at the lower edges 90

of its side walls which rest on the roof sheathing on opposite sides of the ridge line. The ridge pivot piece 19 is rigidly secured to the car by means of a vertical bolt 21 having its head portion seated in a circular depression 22 provided therefor in the web or top portion of said ridge pivot piece. The convex sides 23 of the convexo-convex ridge piece are formed by bowing the side flanges thereof outwardly from end to end. The 100 convex sides 23 of the ridge piece cooperate with the outer surfaces of the straight ridge flanges 11 of adjacent sheets midway of their ridge ends; and the width of said ridge piece is such that when the convex sides of 105 said ridge piece are in engagement with said ridge ends of the sheets, the convex sides of the crescent shaped bosses in the bodies of

2
said sheets are in contact with the sides of the ridge seam cover.

By the arrangement described, the sheets are adapted to accommodate themselves automatically to the distortions of the car frame which occur in service by a rocking movement of their ridge seam flanges on the convex sides of the ridge pieces or by a rocking movement of the convex surface of 10 the crescent bosses on the side walls of the ridge seam covers. The roof sheets are also held against outward sliding movement by the crescent shaped bosses therein and are spaced apart at the middle of their ridge 15 ends by means of the convexo-convex or lens shaped ridge piece.

In the modified construction shown in Figs. 4 and 5, the separate ridge pivot pieces 19 are dispensed with and the ridge 20 ends of the adjacent sheets are spaced apart midway of their length by means of a circular pivot boss 24 pressed in the top or web portion of the channel-shaped ridge seam cover 13^a. In order to prevent moisture from accumulating in the depression formed by the circular pivot boss 24 in the top of the ridge seam cover, said cover is provided with drain channels 25, which extend from side to side of the seam cover 25 on opposite sides of said pivot boss and communicate with said depression by means of branch channels 26. The top of the ridge seam flange of each sheet is provided with transverse grooves 27 which receive the 35 transverse ribs formed in the under side of the cap by the transverse drain channels 25, said grooves being wide enough to permit their side walls to clear said ribs during the rocking movement of the crescent bosses and 40 ridge flanges of the sheets on the sides and pivot boss, respectively, of the ridge seam cover.

My invention is not restricted to the precise forms and arrangements shown.

45 What I claim is:

1. A flexible car roof comprising roof sheets spaced apart along their adjacent margins, a seam cover covering the spaced margins of adjacent sheets, and a pivot 50 member secured to the car beneath said seam cover with its pivot portion disposed entirely between the opposing surfaces of the spaced margins of adjacent sheets, the opposite faces of said pivot member being shaped 55 and arranged to contact with the opposed surfaces of the marginal edges of adjacent sheets for a portion of their length only.

2. A flexible car roof comprising roof sheets spaced apart along their adjacent 60 margins, a seam cover covering the spaced margins of adjacent sheets, and a pivot member secured to the car beneath said seam cover and disposed entirely between the spaced margins of adjacent sheets, said 65 pivot member being shaped and arranged

to contact with the marginal edges of adjacent sheets for a portion of their length only, and said sheets being provided with raised ribs that are shaped and arranged to contact with the sides of said seam cover for 70 a portion of its length only.

3. A flexible car roof comprising roof sheets spaced apart along their adjacent margins, and a seam cover straddling said margins, said sheets being provided intermediate the length of their adjacent margins with relatively short and narrow upstanding ribs that have convex surfaces that extend longitudinally of said seam cover and engage the sides thereof. 80

4. A flexible car roof comprising roof sheets spaced apart along their adjacent margins, and a seam cover straddling said margins, said sheets being provided intermediate the length of their adjacent margins with upstanding ribs that have convex surfaces that extend longitudinally of said seam cover and engage the sides thereof, and a pivot member secured to the car beneath said seam cover and between the spaced margins of adjacent sheets, said pivot member being formed with convex surfaces that extend longitudinally of said margins and cooperate therewith. 85

5. A flexible car roof comprising roof sheets spaced apart along their adjacent margins and having upstanding flanges along said margins, a seam cover straddling adjacent seam flanges, and a pivot member secured to the car and having a pivot portion disposed entirely between the opposing surfaces of adjacent sheet flanges and having convex sides adapted to cooperate with said flanges. 90

6. A flexible car roof comprising roof sheets spaced apart along their adjacent margins and having upstanding flanges extending along said margins, a seam cover straddling adjacent seam flanges, said sheets being provided with convex surfaces adapted 105 to engage the sides of said seam cover, and a pivot member secured to the car between adjacent sheet flanges and having convex sides adapted to cooperate with said flanges. 110

7. A flexible car roof comprising roof sheets spaced apart along adjacent margins, and having upstanding seam flanges along said margins, a seam cover secured to the car and straddling the seam flanges of adjacent sheets, and an inverted channel-shaped pivot 115 member secured to the car between adjacent sheet flanges midway of the length thereof and having convex sides cooperating therewith, said sheets being provided adjacent to said pivot with upstanding bosses that are 120 located inside of said seam cover and are provided with convex surfaces adapted to cooperate with the sides thereof. 125

8. A flexible car roof comprising roof sheets spaced apart along their adjacent 130

margins, and a seam cover secured to the car and straddling said margins and having a circularly bossed portion extending between said margins for cooperation therewith.

5 9. A flexible car roof comprising roof sheets spaced apart along their adjacent margins, and having upstanding seam flanges along said margins, and a seam cover of substantially inverted channel-shaped cross-section secured to the car and straddling said adjacent seam flanges, the top of said seam cover being provided with a downwardly projecting circular boss which extends between said seam flanges.

10 15. 10. A flexible car roof comprising roof sheets spaced apart along their adjacent margins, and having upstanding seam flanges along said margins, and a seam cover of substantially inverted channel-shaped cross-section secured to the car and straddling said adjacent seam flanges, the top of said seam cover being provided with a downwardly projecting circular boss which extends between said seam flanges, and said sheets being provided opposite the bowed portion of said seam cover with upstanding bosses having convex surfaces adapted to cooperate with the sides of said seam cover.

11 20. 11. A flexible car roof comprising roof sheets spaced apart along their adjacent margins, and having upstanding seam flanges along said margins, and a seam cover of substantially inverted channel-shaped cross-section secured to the car and straddling said adjacent seam flanges, the top of said seam cover being provided with a downwardly projecting circular boss which extends between said seam flanges, and said

wardly projecting circular boss which extends between said seam flanges, and said sheets being provided opposite the bowed portion of said seam cover with upstanding 40 bosses having convex surfaces adapted to cooperate with the sides of said seam cover, the top of said seam cover being provided with drainage grooves that lead from the depressions formed in the top of said cover 45 by said circular boss to the sides of said seam covers.

12. A pivot member for flexible car roofs, said member comprising an inverted channel-shaped body whose opposing side walls 50 are bowed outwardly from end to end to form convex surfaces at the sides of said member, said member being provided with outstanding base flanges at the lower edges of its side walls.

55 13. A seam cover for flexible car roofs, said seam cover comprising an inverted channel-shaped member having a circular boss projecting on the under surface of its top or web portion.

60 14. A seam cover for flexible car roofs, said seam cover comprising an inverted channel-shaped member having a hollow circular boss projecting on the under surface of its top or web portion, said boss forming 65 a circular depression in the top of said seam cover, said seam cover being provided with a drain channel which leads from said depression to one side of said seam cover.

Signed at New Kensington, Pa., this 4th 70 day of December, 1926.

CHARLES DAVID BONSALL.
